US00D757099S

(12) **United States Design Patent**
Seo et al.(10) **Patent No.:** US D757,099 S
(45) **Date of Patent:** ** May 24, 2016(54) **DISPLAY SCREEN OR PORTION THEREOF
WITH GRAPHICAL USER INTERFACE**(71) Applicant: **Samsung Electronics Co., Ltd.**,
Suwon-si (KR)(72) Inventors: **Jang-Won Seo**, Seoul (KR);
Yong-Hwan Kwon, Sungnam-Si (KR);
Ji-Eun Kim, Suwon-si (KR); **Ji-Hong Kim**, Seoul (KR); **Hye-Ryung Kim**, Sungnam-Si (KR); **Se-Ran Jeon**, Seoul (KR); **Woo-Seok Hwang**, Seoul (KR)(73) Assignee: **Samsung Electronics Co., Ltd.**,
Suwon-si (KR)(**) Term: **14 Years**(21) Appl. No.: **29/459,641**(22) Filed: **Jul. 2, 2013**(30) **Foreign Application Priority Data**

Jan. 4, 2013 (KR) 30-2013-0000421

(51) LOC (10) Cl. **14-04**

(52) U.S. Cl.

USPC ..... **D14/489**(58) **Field of Classification Search**

USPC D14/489-494, 218

CPC H04N 5/44543; H04N 1/00424

(57) **CLAIM**

The ornamental design for a display screen or portion thereof with graphical user interface, as shown and described.

DESCRIPTION

FIG. 1 is a front view of a display screen or portion thereof with graphical user interface, showing our new design; and, FIG. 2 is a front view thereof, shown in an example environment.

The broken lines define the bounds of the claimed design and form no part thereof.

1 Claim, 2 Drawing Sheets
